UNITED STATES PATENT OFFICE.

HOWARD A. THOMPSON, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed March 1, 1927. Serial No. 171,737.

My invention relates to railway traffic controlling apparatus, and particularly to apparatus of the type wherein train governing current is supplied to the track rails for the control of governing means on the train. More particularly my present invention relates to the trackway portion of such apparatus.

I will describe one form of railway traffic controlling apparatus embodying my invention, and will then point out the novel features thereof in claims.

The accompanying drawing is a diagrammatic view showing one form of apparatus embodying my invention.

Referring to the drawing, the reference characters 1 and 1^a designate the track rails of a railway track along which traffic normally moves in the direction indicated by the arrow. These rails are divided by insulated joints 2 into a plurality of blocks A—B, B—D, etc., of which only one complete block A—B is shown in the drawing. This block A—B is further divided by insulated joints 2 into a rear section A—X and a forward section X—B, but block B—D is not so divided.

Each section of the block A—B is provided with a track relay, the relay for the rear section being designated R^A and the relay for the forward section being designated R^X. Block B—D is likewise provided with a track relay R^B. Each track relay comprises a winding 3 connected across the rails of the associated section or block, and a winding 4 constantly supplied with alternating current from the secondary 19 of a transformer designated by the reference character L with a distinguishing exponent. The primary 18 of each transformer L is constantly supplied with alternating current from a transmission line 20. Alternating track circuit current is supplied to the rails of each section and block for the energization of track relay winding 3 in the manner hereinafter explained. For present purposes it will be sufficient to state that each track relay is closed when the associated section or block is unoccupied, and is open when the section or block is occupied.

Each block is provided with a distant relay designated by the reference character E with an exponent corresponding to the location. Referring to relay E^A, the winding

for this relay is from secondary 19 of transformer L^B, through wire 66, contact 80 of track relay R^B, wire 81, contact 82 of track relay R^X, wire 83, winding 15 of relay E^A, wire 84, contact 85 of track relay R^X, wire 86, contact 87 of track relay R^B, and wire 55 to secondary 19 of transformer L^B. It follows that relay E^A is closed when track relays R^X and R^B are both closed, and open when either of these track relays is open.

Located at the point X is a relay L^X, the winding of which is connected by wires 92 and 93 with the wires 83 and 84 in the circuit for relay E^A. It follows therefore that when section X—B and block B—D are unoccupied, relay F^X will be energized, but that it will be de-energized when either track relay R^X or R^B is open.

Located at the point A is a home relay H^A, the circuit for which passes from the secondary 19 of transformer L^X, through wires 38 and 68, front contact 69 of track relay R^X, wire 70, contact 71 of track relay R^A, wire 72, winding of relay H^A, wire 73, front contact 74 of track relay R^A, wire 75, contact 76 of track relay R^X, and wires 77 and 41 to the secondary 19 of transformer L^X. It will be seen, therefore, that relay H^A is energized when both track relays R^A and R^X are closed, but de-energized when either of these track relays is open. Block B—D is not provided with a home relay because this block comprises only one section and so the track relay R^B functions as a home relay.

Each section and each block is provided with a three-position repeater relay designated by the reference character P with an exponent corresponding to the location. Each relay P comprises a winding 12 constantly supplied with alternating current from the secondary 19 of the associated transformer L, and a second winding 13. Referring particularly to repeater relay P^X, winding 13 of this relay is supplied with alternating current from a transformer G^A located at the point A, the primary 22 of which transformer is constantly connected with the secondary 19 of transformer L^A. The right-hand terminal of winding 13 of relay P^X is connected with a mid point in the secondary 23 of transformer G^A by a wire 24. The left-hand terminal of winding 13 of relay P^X is connected with the lower or

the upper terminal of secondary 23 according as track relay R^A is closed or open. When track relay R^A is closed, the circuit for winding 13 of relay P^x passes from the 5 lower terminal of secondary 23, through wire 25, front contact 26 of track relay R^A , wire 27, winding 13 and wire 24 to the mid point of secondary 23. When track relay R^A is open, the circuit for winding 13 is from 10 the upper terminal of secondary 23, through wire 28, back contact 26 of track relay R^A , wire 27, winding 13 and wire 24 to the mid point of secondary 23. It follows that alternating current of one relative polarity or 15 the other will be supplied to winding 13 according as track relay R^A is closed or open. When track relay R^A is closed, winding 13 is energized with current of what I will term "normal" relative polarity and contact fingers 20 40, 50 and 31 of relay P^x are then swung to their left-hand positions. When track relay R^A is open, winding 13 is supplied with alternating current of what I will term "reverse" relative polarity, so that 25 the contacts of relay P^x are swung to their right-hand positions.

Referring now to relay P^B , the right-hand terminal of winding 13 is connected with the mid point of secondary 23 of 30 transformer G^x through wire 29, whereas the left-hand terminal of winding 13 is connected with secondary 23 through a path which includes contact 33 of track relay R^x and which at times includes contact 31 of repeater relay P^x . When track relay R^x is closed and repeater relay P^x is energized in the normal direction, the circuit for winding 13 of relay P^B is from the lower terminal of secondary 23 of transformer G^x , through 35 wire 30, normal contact 31 of relay P^x , wire 32, front contact 33 of track relay R^x , wire 34, winding 13 of relay P^B and wire 29 to the mid point of secondary 23. Repeater relay P^B is then energized in the normal direction. If relay P^x is energized in the reverse direction, however, while relay R^x is closed, the circuit for winding 13 of relay P^B is open at contact 31, so that this relay is de-energized with the result that its back or 40 intermediate contacts are closed. When track relay R^x is open, the circuit for winding 13 of relay P^B is from the upper terminal of secondary 23 of transformer G^x , through wire 35, back contact 33 of track relay R^x , 45 wire 34, winding 13 and wire 29 to the mid point of secondary 23. The current which is then supplied to winding 13 is of reverse relative polarity, so that the contacts of relay P^B are swung to their right-hand positions. 50

Current is supplied to the track rails of each section and each block by a transformer designated by the reference character T with an exponent corresponding to the location. Secondary 37 of each transformer T 55

is constantly connected with the track rails of the associated section or block, and the supply of current to the primary 36 of each transformer T is controlled by the associated repeater relay P . Referring particularly to 70 transformer T^x , when repeater relay P^x is energized in the normal direction, current is supplied to the primary 36 of transformer T^x by a circuit which passes from the secondary 19 of transformer L^x , through wires 41 and 67, normal contact 40 of relay P^x , wire 39, primary 36 of transformer T^x , and wire 38 to secondary 19 of transformer L^x . Uninterrupted alternating current is then supplied to the rails of section A—X, so 75 that track relay R^A is closed. If relay P^x is energized in the reverse direction, however, this circuit for primary 36 of transformer T^x is open at contact 40, and the supply of alternating current to primary 36 is periodically interrupted by a coding device C^x . This coding device comprises a motor 5 operating a plurality of cams 6 and 7, which cams control contacts 9 and 10 respectively. When relay P^x is energized in the 80 reverse direction, the motor 5 of the coding device C^x is energized by a circuit which passes from the secondary 19 of transformer L^x , through wires 41 and 51, reverse contacts 50 of relay P^x , wire 49, windings of motor 95 5 and wires 48 and 38 to the secondary 19 of transformer L^x . Assuming that relays R^x and L^x are both closed, the circuit for the primary of transformer T^x is from the secondary 19 of transformer L^x , through wires 100 41 and 67, wire 47, contact 10 of coding device C^x , wire 46, front contact 53 of relay L^x , wire 44, front contact 43 of track relay R^x , wire 42, reverse contact 40 of relay P^x , wire 39, primary 36 of transformer T^x , and wire 38 to secondary 19 of transformer L^x . Owing to the periodic operation of contact 10 by cam 7 of the coding device C^x , the alternating current thus supplied to transformer T^x will be periodically interrupted 105 for the purpose of controlling suitable train-carried governing apparatus which forms no part of my present invention. If track relay R^x is closed, and relay L^x is open, the circuit for the primary of transformer T^x will include contact 9 of the coding device C^x and the back point of contact 53 of relay L^x . This latter circuit has nothing to do with my present invention except in so far as it includes reverse contact 40 of relay P^x , 110 and, consequently, it is not traced in detail herein. 115

Referring now to transformer T^B , uninterrupted alternating current is supplied to the primary 36 of this transformer when relay P^B is energized in the normal direction and also when this relay is de-energized, the circuit being from the secondary 19 of transformer L^B , through wires 55 and 68, contact 40 of relay P^B in the normal or the de-ener- 120 125 130

gized position, wire 39, primary 36 of transformer T^B and wire 66 to secondary 19 of transformer L^B . When relay P^B is energized in the reverse direction, this circuit is open, 5 and the alternating current supplied to the primary of transformer T^B is periodically interrupted by one of the contacts of the coding device C^B , dependent on the conditions of relays R^B and E^B . The circuits for 10 accomplishing this are similar to the circuits controlled by coding device C^x , and they have nothing to do with my present invention except in so far as they include the contact 40 of relay P^B in its reverse position. 15 These circuits are therefore not traced in detail herein.

Located at the entrance end of each block is a signal designated by the reference character S with an exponent corresponding to 20 the location, each of which signals in the form here shown comprises a proceed lamp 21^G , a caution lamp 21^Y and a stop lamp 21^R . Referring particularly to signal S^B , the circuit for the proceed lamp 21^G is from the 25 secondary 19 of transformer L^B , through wire 55, front contact 57 of track relay R^B , wire 58, front contact 59 of relay E^B , wire 62, lamp 21^G , wire 63, contact 64 of relay P^B in the reverse or the de-energized position, 30 and wires 65 and 66 to secondary 19 of transformer L^B . It will be noted that this circuit includes contact 64 of relay P^B , which contact is open when the relay is energized in its normal direction, so that normally lamp 35 21^G is extinguished. The circuit for each of the remaining lamps of signal S^B includes contact 64 of relay P^B , so that none of the lamps of this signal are lighted when relay P^B is energized in the normal direction. 40 The circuits for lamps 21^Y and 21^R are not traced herein because they form no part of my present invention except in so far as they are controlled by contact 64 of relay P^B .

The circuits for signal S^A are similar to 45 those for signal S^B , except that they are controlled by relay H^A instead of the track relay R^A . The circuit for each lamp in signal S^A is controlled by contact 64 of relay P^A in the same manner that the circuits for signal 50 S^B are controlled by contact 64 of relay P^B .

When the track is unoccupied, each relay P is energized in the normal direction, so that uninterrupted alternating current is supplied to the track rails and all the lamps of each 55 signal are extinguished. When a train passes point A, it opens track relay R^A , thereby reversing at contact 26 the relative polarity of the current supplied to winding 13 of relay P^x , so that this relay reverses. 60 Periodically interrupted alternating current is then supplied to the rails of section A-X through one of the contacts of the coding device C^x . The circuit for winding 13 of relay P^x is opened at contact 31 of relay P^x , so 65 that the contacts of relay P^B assume their in-

termediate positions. One or another of the lamps of signal S^B then becomes lighted through contact 64 of relay P^B , but the supply of track circuit current to section X-B is still uninterrupted. When the train enters section X-B it opens track relay R^x , so that current of reverse relative polarity is supplied to winding 13 of relay P^B through back contact 33 of track relay R^x . Relay P^B is therefore energized in the reverse direction, so that the supply of uninterrupted alternating current to the rails of section X-B is discontinued and periodically interrupted alternating current is supplied to the rails of this section through one or the other of the contacts of the coding device C^B .

Although I have herein shown and described only one form of apparatus embodying my invention, it is understood that various changes and modifications may be made therein within the scope of the appended claims without departing from the spirit and scope of my invention.

Having thus described my invention, what I claim is:

1. In combination, a stretch of railway track divided into a rear and a forward block, the rear block being further divided into a rear and a forward section, a normally closed track relay for each section, a three-position repeater relay for each section, means controlled by each repeater relay for supplying the associated section with uninterrupted alternating track circuit current when the relay is energized in normal direction and when it is de-energized and with periodically interrupted alternating current for automatic train control purposes when the relay is energized in reverse direction, a signal for said forward block, means for opening all circuits for said signal when the repeater relay for the forward section is energized in normal direction and for permitting them to be closed when the relay 95 is energized in reverse direction and when it is de-energized, means for energizing each repeater relay in normal or reverse direction according as the track relay for the corresponding section is closed or open, and means for de-energizing the repeater relay for the forward section when the repeater relay for the rear section is energized in the reverse direction and the track relay for the forward section is closed.

2. In combination, a section of railway track, a normally closed track relay for said section, a three-position repeater relay for said section, means controlled by said repeater relay for supplying uninterrupted alternating track circuit current to the rails of said section when the repeater relay is energized in normal direction and for supplying periodically interrupted alternating current to the rails of the section for auto- 125

matic train control purposes when the repeater relay is energized in reverse direction, and means for energizing said repeater relay in normal or reverse direction according as said track relay is closed or open.

3. In combination, a stretch of railway track divided into a rear and a forward block, the rear block being further divided into a rear and a forward section, a normally closed track relay for each section, a three-position repeater relay for each section, means controlled by each repeater relay for supplying the associated section with uninterrupted alternating track circuit current when the relay is energized in normal direction and when it is de-energized and with periodically interrupted alternating current for automatic train control purposes when the relay is energized in reverse direction, means for energizing each repeater relay in normal or reverse direction according as the track relay for the corresponding section is closed or open, means for de-energizing the repeater relay for the forward section when the repeater relay for the rear section is energized in the reverse direction and the track relay for the forward section is closed, and a signal for the forward block approach-controlled through a reverse contact and also through a back contact of the repeater relay for the forward section of the rear block.

4. In combination, a section of railway track, a normally closed track relay for said section, a three-position repeater relay for said section, means controlled by said repeater relay for supplying uninterrupted alternating track circuit current to the rails of said section when the repeater relay is energized in normal direction and for supplying periodically interrupted alternating current to the rails of the section for automatic train control purposes when the repeater relay is energized in reverse direction, said repeater relay having two windings one of which is constantly supplied with alternating current of fixed relative polarity, a transformer the primary of which is constantly supplied with alternating current of fixed relative polarity, means for constantly connecting one terminal of the remaining winding of said repeater relay with a mid point in the secondary of said transformer, and means for connecting the other terminal of said remaining winding with one terminal of said secondary through a front contact of said track relay and with the other terminal of said secondary through a back contact of said track relay, whereby said repeater relay is energized in normal or reverse direction according as said track relay is closed or open.

In testimony whereof I affix my signature.
HOWARD A. THOMPSON.
